UNITED STATES PATENT OFFICE.

FELIX KOCH, OF BELLEVUE, PENNSYLVANIA, ASSIGNOR TO PRERESSED STEEL CAR COMPANY, OF PITTSBURGH, PENNSYLVANIA, A CORPORATION OF NEW JERSEY.

ANCHORAGE FOR VESTIBULE MEMBERS OF ARTICULATED CARS.

Application filed July 26, 1927. Serial No. 208,434.

This invention relates to articulated cars and has for an object the provision of means for anchoring the vestibule member of an articulated car to its support. 5
A further object of the invention being the provision of means to maintain a vestibule member of an articulated car in proper position, with relation to the adjacent bodies, whenever said car is traversing 10 curves or uneven portions of railroad track.

These and further objects will be apparent from the following description.

Fig. 1 is a plan view of the vestibule member showing its relation to the adjacent 15 ends of two adjacent bodies and the truck common to both bodies, when the cars are in a straight line; Fig. 2 is a plan view of the same bodies and shows the relation of the vestibule member to them while they 20 are rounding a curve; Fig. 3 is a sectional view taken along the lines A—A on Fig. 1 and shows the vestibule member in conjunction with its anchorage; Fig. 4 is a sectional view taken along the lines A—A of Fig. 1 25 and shows the action of the anchor rods when the vestibule member is tilted as with the rocking of the car bodies or the turning of the vestibule member when rounding a curve; Fig. 5 is an enlarged detail of one 30 of the anchor members.

As shown by the drawings the invention is embodied with a vestibule supported on one of the adjacent ends of two adjacent bodies. It is to be understood, however, 35 that I do not desire to limit myself to this specific mode of supporting the vestibule member for it can be supported equally as well on the truck or any other suitable bearing.

Referring now in detail to the drawings the reference character 1 indicates a vestibule member, of the preferred cylindrical form, with a passageway 2 formed therein. At the base of the vestibule is shown the 40 bearing member 3 supported in its base 4. This base member 4 is better shown in Figs. 1 and 2 and in the present form is fastened to the underframe 5 of one of the bodies and extends between the two bodies above 45 their common truck. The underframe 5 referred to is supported, with the adjacent end of the other member of the articulated car, in a bearing 6 which may be of any suitable form and carried by a truck, the bolster 7 of which is shown in the drawings. The

anchor rods 8 are attached at the side of the vestibule member 1 by suitably arranged brackets 9. At the other ends of the rods 8 are shown brackets 10 cooperating with eyes 11 on the rods to fasten them to the truck 50 bolster 7.

When the vestibule member is normal to the truck the rods serve the purpose of keeping the vestibule member in an upright position and prevent any undue vertical displacement. While the cars are traversing 55 a curve the vestibule is turned relative to the bodies so as to form at all times a continuous passageway between the two adjacent bodies, this position being shown in Fig. 70

2. As will be seen from the drawings this horizontal movement of the vestibule member without any corresponding vertical displacement requires a lengthening of the anchor rods. This compensating movement is 75 taken care of by the washers 12 and 13 with the spring 14 as shown in detail in Fig. 5. The upper washer 12 is fastened to the rod 8, but the lower washer 13 is free to move 80 on the rod. The spring 14 bearing in cups 15 of the washers serves to separate them and keeps a tension at all times between the washers to maintain the rod 8 at a proper 85 operating length. The bracket 9 is provided with a portion which is slightly curved 90 at the point where the rod 8 passes through it and corresponds to the contour of the contacting washer 13 to allow the rod 8 to tilt with any movement of the vestibule.

During any swaying of the car bodies and 90 corresponding movement of the vestibule, the spring 14 in conjunction with the washers 12 and 13 allows freedom of movement between the brackets 9 and the rods 8, thus 95 it will be seen that while the vestibule is at all times positively connected to the underframes or trucks, by the anchor members, there is also freedom of movement provided 100 between these anchors and the vestibule member.

Having thus described my invention what I claim as new and desire to secure by Letters Patent is:

1. In an articulated car, adjacent ends of two adjacent bodies supported on a common 105 truck, a vestibule member, spanning the space between said bodies and supported in a pivot bearing secured only to one car body, an anchor rod connected to said vestibule and said truck, said rod being adapted 110

to maintain said vestibule in its bearing during operation of said articulated car.

2. In an articulated car, adjacent ends of two adjacent bodies supported on a common truck, a vestibule member between said bodies and supported in a pivot bearing secured only to one car body, anchor rods on said vestibule to maintain said vestibule in connected relation with the bodies and truck at all times, said anchor rods being flexibly connected at both ends thereof.

3. In an articulated car, adjacent ends of two adjacent bodies supported on a common truck, a vestibule member spanning the space between the bodies and supported in a suitable bearing, anchor rods on either side

of said vestibule member connected to the truck, said rods having compensating means at one end and rotatably connected at the other end to hold said vestibule member in place during the operation of the car.

4. In an articulated car, adjacent ends of two adjacent bodies resting on a common truck, a vestibule member, between said bodies, anchor rods at each side thereof, eyes on one end of each of said rods and a spring controlled sliding connection at the other ends thereof, for adjusting said rods to tilting or twisting movements of said vestibule member when the car is in motion.

In testimony whereof I affix my signature.

FELIX KOCH.
